INKSTAND

Francisco Lago, Livingston, N. Y.

Application August 17, 1946, Serial No. 691,215

1 Claim. (Cl. 120—4)

1

This invention relates to a combined ash tray and ink stand.

It is an object of the present invention to provide a combined ash tray and ink stand which not only has utility but which is ornamental in its appearance and constructed from a hat shape body.

It is another object of the present invention to provide an ash tray which can be readily converted into an ink stand by removal or hinging over a top part of the hat shape so as to expose a removable ink well and at the same time provide a pen holder of the interior of the cover as it is inverted and hinged back.

According to the present invention, a piece of metal or other suitable material of hat configuration is worked into such shape that its hat brim portion serves as a dish for receiving cigarette and cigar ashes. The crown in the center of the brim is split horizontally to provide a top removable portion. This removable portion is hinged so as to be lifted up and to the rear and adapted to be retained in an inclined position to receive and hold a pen when not in use. Within the fixed portion of the crown there is disposed a removable ink well from which ink can be taken by the pen when it is to be used. This ink well is raised in the rear portion and has an indentation along its rear edge so that the pen when being retained in the holder is prevented from moving laterally and is accordingly steady within the holder. The ink well is carried on two fixed trunnions and can swivel slightly fore and aft so that as the pen is wiped upon a lateral edge within the ink well there will be a slight give to the ink well and thereby render the wiping action of the pen more effective as the ink well or lateral edge will tend to adjust itself to the inclination of the pen as it is worked on the lateral edge.

If desired, other items than an ink well may be used in the fixed crown portion. For instance, a cigarette lighter may be disposed in the fixed crown portion with the removable or hinged top portion serving as a cover for the latter and adapted when being closed to snuff out the lighter flame.

For further comprehension of the invention, and of the objects and advantages thereof, reference will be had to the following description and accompanying drawings, and to the appended claim in which the various novel features of the invention are more particularly set forth.

In the accompanying drawing forming a material part of this disclosure:

Fig. 1 is a side elevational view of the combined

2

tray and stand with the top portion closed upon the fixed crown portion when the ink is not being used.

Fig. 2 is a cross sectional view, the ink well being exposed and shown only partially in section, the same being carried by its recesses at opposite sides fitted over fixed trunnions on the stationary crown portion.

Fig. 3 is a top plan view of the combined tray and stand with the top portion still closed as in Fig. 1.

Fig. 4 is a cross sectional view taken through the combined tray and stand at an angle ninety degrees from the cross section of Fig. 2, whereby to show more clearly the catch which is used to hold the top portion in its closed position.

Fig. 5 is an enlarged perspective view of the ink well removed from the tray and stand.

Fig. 6 is a side elevational view with the top portion hinged back and a pen resting in the top portion and upon the rear edge of the ink well.

Referring now to the figures, 12 indicates my combined ash tray and ink stand having a turned up brim portion 13, a tall crown comprising a fixed crown portion 14 and a hinged cover or top portion 15. The crown in its entirety is tapered from its bottom to near a point at its top and the device 12 has the appearance of a sombrero.

The brim portion 13 by being turned up provides a space 16 accessible from the top and suitable for the deposit of cigarettes and their ashes. Its bottom portion 17 provides a support therefor. Extending inwardly from the rim edges are four shelves 18 concaved to receive the sides of cigarettes and on which the cigarettes are rested when they are to be used again.

The crown portion 14 is hollowed out, as indicated at 19. This hollow portion tapers from the bottom toward the top in conformity with the external face of the crown portion whereby to provide an area within the hollow portion 19 near the bottom which is wider or of greater diameter than the area at the top of the bottom crown portion where the top cover is connected.

Near the top of the crown portion 14, there extends inwardly from diametrically opposite portions, trunnion pins 21 on which an ink well 22 is rested for tilting movement.

The ink well 22 is generally of cylindrical shape having a closed bottom and an open top. The top extends out of and above the top of the fixed crown portion 14. Just below the top and at opposite sides of the ink well are respectively flanges 23 having recesses 24 open at their bottom ends to receive the trunnion pins 21 and closed

at their top ends to provide a journal bearing support for the ink well. With the ink well so mounted, it can tilt fore and aft. This movement is helpful when a pen, indicated at 25, is brushed across the top edge of a partition wall 26 in the top of the ink well. The bearing force, which can be applied to the pen point, is accordingly limited and if too great the well will tilt forwardly so that its bottom end will strike against the hollowed interior wall surface 19 and thus by the well becoming rigid with the crown portion 14 for the moment the user of the pen will be warned of his using too much wiping force in the brushing of the pen point.

The cover 15 is retained by a hinge 27 and a catch 28. When the cover 15 is closed, the catch 28 which extends along the interior surface 19, locks over an inwardly extending projection or lip 29 on the edge of the cover opposite to the hinge 27. The catch 28 is made of spring material and is anchored by a rivet 31 near the bottom of the stationary crown portion 14. An operating projection 32 is located near the upper end of the spring catch 28 and extends through a hole 33 to be accessible for operation by the user of the device. The hinge 27 may include a spring 35 so that the top portion 15 will jump open when released to the wide open position, shown in Fig. 6.

The top of the ink well is raised at the rear and has a recess 36 adapted to receive the side of the pen 25 so that when the pen is out of use it can be steadied by the ink well top while the pen point is located in the opened cover 15, all in the manner shown in Fig. 6. When it is again desired to use the pen it is readily accessible and can be taken from the cover and dipped again in the ink well.

While the device has been described as providing for the insertion of an ink well it will be understood that when it is not desired to use it as an ink well, other devices such as cigarette lighters can be inserted in the crown portion in the same manner that the ink well has been inserted.

Also the ink well itself when not used to contain ink may serve as a device for assisting in the snuffing out of a cigarette. The head end of the cigarette will be disposed over the ink well partition 26 in the top thereof and fore and aft movement will be applied to snuff out the cigarette. The tilting movement favors the action and makes it easier to snuff out the cigarette.

While I have illustrated and described the pre-

ferred embodiments of my invention, it is to be understood that I do not limit myself to the precise constructions herein disclosed and the right is reserved to all changes and modifications coming within the scope of the invention as defined in the appended claim.

Having thus described my invention, what I claim as new, and desire to secure by United States Letters Patent is:

- 10 In a device of the class described having a base with an open topped hollow tubular portion extended upward therefrom, a receptacle for containing ink positioned within the tubular portion, and a hollow cover portion closing the top of the tubular portion, said cover portion being hingedly connected to the tubular portion to be pivoted to a downwardly and rearwardly inclined position to receive the nib of a pen, said receptacle being formed at its side adjacent the point of pivotal 15 attachment of said cover portion with an upwardly extended portion projected above the top of the tubular portion, said upwardly extended portion having a recess in its top edge, whereby when said cover portion is pivoted to its rearwardly inclined position a pen can be supported in a forwardly and upwardly inclined position with its nib resting in said cover portion and its holder resting in said recess.

FRANCISCO LAGO.
